C. Muller.

Mach. for Casting Type.

N° 10377.

Patented Jan. 3. 1854.

UNITED STATES PATENT OFFICE.

CHARLES MÜLLER, OF NEW YORK, N. Y.

IMPROVEMENT IN MACHINES FOR CASTING TYPE.

Specification forming part of Letters Patent No. 10,377, dated January 3, 1854.

To all whom it may concern:

Be it known that I, CHARLES MÜLLER, of the city, county, and State of New York, have invented certain new and useful Improvements in Machines for Casting Type; and I do hereby declare that the following is a full, clear, and exact description of the same, reference being had to the accompanying drawings, forming part of this specification, in which—

Figure 1 is a perspective view of a machine constructed according to my invention. Fig. 2 is a plan or top view of the cam and mechanism combined therewith for opening the mold. Fig. 3 is a side view of the lever for tilting the matrix.

Similar letters of reference indicate corresponding parts in the several figures.

The first part of my invention consists in placing the mold below its axis of oscillation, instead of in its usual position above. By this change of position, if the mold is hung at a proper distance from the nipple or opening through which it receives the melted metal, its tendency toward its center of gravity will act in opposition to the momentum it acquires in its oscillation, and will thus reduce the force of its concussion against the nipple, which is highly injurious to the machine, and also the shock at the end of its movement from the nipple. This change of position admits of a reduced movement of the mold from the nipple and a reduced degree of opening to be given to release the type from the mold and allow it to fall out, as when released no obstruction is offered to it. The decreased movement of the mold does not give it so great a momentum, and this, also, tends to reduce the concussion. The decreased opening of the mold reduces the friction of its sides and the consequent wear.

The second part of my invention consists in a simple combination of mechanism for opening the mold.

The third part of my invention consists in certain simple means of tilting the matrix.

To enable those skilled in the art to make and use my invention, I will proceed to describe its construction and operation.

A A' are the standards, in the upper ends of which are two center screws, a a, which support the horizontal shaft S, which forms the center of oscillation of the type-mold.

B B are the connected oscillating arms which carry the mold-blocks and mold, holding them suspended as a pendulum from the axis S. The oscillating arms and the mold are substantially similar to those of other machines, one portion, C, of the mold being attached immovably to one of the oscillating arms, and the other portion, C', being suspended on a pivot, b, on the other arm in such a way that, while it oscillates with the arm and the other part, C, of the mold, it is capable of oscillating in a direction at right angles thereto for the purpose of opening the mold and releasing the type when cast.

D is the matrix, which occupies its usual position in relation to the mold, and is held in place by an arched spring, c. The metal pot occupies its usual position at the back of the mold.

The driving-shaft E, through which the oscillating motion is given to the mold and the necessary movements are given to the other parts of the machine, is supported in suitable bearings, d d, in front of the standard A. It gives motion to the shaft S for the purpose of moving the mold toward and from the nipple by means of a crank-pin, F, which works in an opening in the lower end of a lever, G g, which is secured to the said shaft S. This lever is in two parts, of which the part G is secured to the shaft, and the part g, in which is the opening in which the crank-pin F works, is attached to the part G by a hinge-joint at e, and is adjustable by a set-screw, f, and clamping-screw h, so as to regulate the movement of the mold and make it move just far enough backward to form a close joint with the female plate of the nipple. The driving-shaft also carries a cam, H, through which the mold is opened during its return from the nipple, and closed previously to or during its movement toward it. This cam consists of a cylinder with a groove in its periphery of such form as to give a vibration back and forth to a lever, I, which works horizontally on a fulcrum, i, secured to the standard A', once during every revolution of the driving-shaft, and holds the said lever stationary for some time at the end of its vibration in each direction, the said lever being furnished with a stud, j, at one end (shown dotted in Fig. 2) to work in the said groove. The opposite end of the lever

I is connected by a rod, J, with the lower end of a lever, K, which vibrates vertically on a fulcrum, k, secured to the standard A, the upper end of the said lever being attached by a rod, L, and universal joints l m with the part C' of the mold. The vibration of the lever I in one direction opens and in the other direction closes the mold, which remains open and closed alternately during the intervals of rest of the lever.

At one side of the lever G g stands a lever, M, whose fulcrum is at its lower end on a pivot, n, suitably secured to the base of the machine. This lever has a slot at about the center of its length, which receives a stud, r, attached to one side of the lever G g, and at its upper end it carries a stud, o. At the bottom a spring, q, secured to the base of the machine, acts upon the lever M with a tendency to throw it forward. On the outside of that part of the vibrating arm which carries the fixed portion C of the mold a small lever, N, works on a fulcrum, p, secured to the arm. The lower end of this lever has a screw, s, in its end, whose point bears against the outer or overhanging end of the matrix D, and its upper end is situated in front of the stud o. The lever M is moved forward by the stud r when the lever G g moves forward to bring the mold away from the matrix, and the stud o is thus caused to push forward the upper end of the lever N and consequently throw back the screw s and tilt the matrix. This takes place simultaneously with the opening of the mold. The spring q exerts sufficient influence on the lever M to keep its stud o bearing against the lever N, and thus keep the point of the screw s always bearing on the matrix when the lever M is not being moved back by the lever G g, though it is not intended to be sufficient to interfere with the operation of the spring c and influence the matrix, but only to keep the parts in operation without clash.

The operation of casting the type is performed in the same manner in this as in other machines, and therefore needs no description.

It will be obvious that the type must be liberated and discharged from the mold with more certainty when in the position shown than when above its axis of oscillation, as the mold only requires to move away from the nipple and to open far enough to allow room for the type to drop out, which it does without impediment, the opening increasing in width toward the bottom.

In addition to the advantage accruing from the facility of the escape of the type, the durability of the machine will be much increased owing to the almost total absence of concussion and the decreased friction.

The arrangement of the several devices for operating the mold is such as to offer no impediment to the adjustment of the mold, as it is left exposed to sight and allows room for any necessary manual operation. The whole machine has, moreover, the advantage of simplicity.

What I claim as my invention, and desire to secure by Letters Patent, is—

1. Suspending the mold below its axis of oscillation, substantially as described, whereby its tendency toward its center of gravity will act in opposition to the momentum required in its movements toward and from the mold, and its movement and degree of opening are enabled to be reduced, producing the results set forth.

2. The combination of the cam H, lever I, rod J, lever K, and rod L, arranged substantially as shown, for the purpose of opening and closing the mold.

3. Tilting the matrix by means of the lever N attached to the oscillating mold-arm, combined, as described, with the lever M, which receives an oscillating motion from the arm or lever by which the oscillating motion is given to the shaft or axis upon which the mold oscillates.

CHS. MÜLLER.
